United States Patent

Des. 234,585
Patented Mar. 25, 1975

234,585

KAYAK

Clement Lacasse, 416 3rd St., Daveluyville,
Quebec, Canada

Filed Jan. 26, 1973, Ser. No. 327,062

Term of patent 14 years

Int. Cl. D12—06

U.S. Cl. D12—63

FIG. 1 is a top plan view;

FIG. 2 is an elevation of one side, the other side being identical;

FIG. 3 is a front end elevation;

FIG. 4 is a bottom plan view; and

FIG. 5 is a longitudinal section taken along the centerline; and

FIGS. 6 and 7 are cross-sections taken along lines 6-6 and 7-7 of FIG. 1, respectively.

I claim:

The ornamental design for a kayak, as shown and described.
